Primary Examiner — Sandra Snapp*Assistant Examiner* — Mehri Bajoul(74) *Attorney, Agent, or Firm* — Cooper & Maersch LLC; Lorri W. Cooper(57) **CLAIM**

The ornamental design for a bubble wand, as shown and described.

DESCRIPTION

FIG. 1 is a front elevational view of a bubble wand showing my new design;

FIG. 2 is a front elevation view of the bubble wand of FIG. 1, the rear view being a mirror image thereof;

FIG. 3 is a left elevation view of the bubble wand of FIG. 1, with the right-side view being a mirror image thereof;

FIG. 4 is a top plan view thereof; and,

FIG. 5 is a bottom plan view thereof.

The evenly dashed lines in FIGS. 1-5 depict portions of the bubble wand that form no part of the claimed design. The dot-dash line is a boundary line and forms no part of the claim.
